UNITED STATES PATENT OFFICE.

WILLIAM S. McCACKEN, OF JOLIET, ILLINOIS.

HORSESHOE.

1,092,585.

Specification of Letters Patent.

Patented Apr. 7, 1914.

Application filed June 20, 1912. Serial No. 704,728.

To all whom it may concern:

Be it known that I, WILLIAM S. McCACKEN, citizen of the United States, residing at Joliet, in the county of Will and State of Illinois, have invented a certain new and useful Improvement in Horseshoes, of which the following is a full, clear, concise, and exact description.

My invention relates to improvements in that class of horse shoes in which the calks are made removable in order that when they become dull or worn, they may be replaced by new ones. I have found that the best construction is to provide three lugs at the toe and three lugs at each of the heel ends of the bar so that the calks may be held each between three abutments. This is of especial importance with respect to the toe calk for the reasons that will be presently explained.

The preferred form of my invention is illustrated in the accompanying drawings, in which—

Figure 1 is a plan view of the underside 25 of a horse shoe embodying my invention; Fig. 2 is a view taken on section line 2—2 of Fig. 1.

Like parts are indicated by similar characters of reference throughout the different 30 views.

The bar 1, it will be seen, is provided with three lugs at the toe and also with the same number at each of the heel ends. At the toe the lugs 2, 3 and 4 form the abutments 35 for supporting the calk 5. The said calk, after being placed in position, is secured by the key or wedge 6 which is driven in as shown between the said calk and the lug 2. These lugs 2, 3 and 4 are provided with 40 bearing surfaces which form a channel so to speak for receiving the calk 5. The lugs 3 and 4 are located upon opposite sides of the center of the bar and their bearing surfaces incline toward the toe, while the lug 45 2 placed at the point of the toe of the shoe constitutes the third abutment or support, and the wedge 6 is driven in as shown; this lug at the toe is inclined toward the heel. There is thus formed a channel which is 50 restricted at the outer portion, and thus the calk may be securely held in place. The bearing surfaces of the lugs 2, 3 and 4 I have shown rounded; moderate change in the curve of the bar at the toe will not 55 change the relative positions of the bearing surfaces.

Referring to the heel ends of the bar the lugs 7, 8 and 9 are of similar construction to the lugs at the toe, and the calks 10 are held in place in a similar manner, a wedge 60 11 in each case being driven in, preferably from the outer sides, respectively, to secure the calks in place in the channels formed by the overhanging lugs.

To more positively keep the calks in position I provide offsets 12 upon the calks, the shoulders which come between the corresponding studs. My shoe may be cast out of malleable iron and after going through the annealing process is ready to nail to the 70 horse's foot, needing no further labor in filing and fashioning the different parts. The shoe, if desired, may be forged or rolled, since the construction is such as to admit of the rolling or forging operation. The calks 75 are made wedge-shaped, their upper or wider edge resting against the surface of the bar while the lugs are shaped to conform to the calks.

Removable calks heretofore have not been 80 introduced practically to a large extent for several reasons, among which may be mentioned the complications introduced in construction and the liability of the parts becoming misplaced when the blacksmith heats 85 the shoe in fitting it to the foot. Any grooves or channels, especially those at the toe, have been liable to be warped so that the calks may not be put in and secured in place without special fitting.

In order to meet the requirements of the present day it is necessary that the bar, lugs and channel be so constructed that when heated and bent to the different shapes required, the relative position of the set of 95 abutments or the direction of the channels intended to support the removable calks may not be changed so as to require special shaping of such channels or abutments or of the calks themselves. It will be seen that the bar of my shoe may be heated at the toe and then spread or contracted without materially changing the position of the lugs relatively.

I have, in some instances, formed the lug 105 2 at the toe with a plain inclined surface with good effect instead of with a rounded surface as shown in the drawings. In winter, when the roads are icy and slippery, I use a sharpened calk that fits in between 110 the lugs the same as the dull calks shown in the drawings. In order to change from one

kind of calk to the other, it is only necessary to drive out the keys and the change is thus readily made upon the street or otherwise.

5 I claim:—

1. In a horse shoe, a bar provided with three lugs at the toe of the shoe, one of said lugs being located centrally of the bar near the forward edge thereof and the other of 10 said lugs being located upon opposite sides of the center of said bar and rearward of said other lug, said lugs having rounded bearing surfaces, a wedge-shaped calk placed between said lugs in the channel formed thereby, and a wedge inserted between the 15 said centrally disposed lug and said calk.
2. In a horse shoe, the combination with

a bar having the lug or abutment at the toe and corresponding abutments 3 and 4 provided with rounded bearing surfaces, of a 20 calk provided with an offset to form shoulders which come between the last mentioned abutments; the wedge or key inserted between said calk and the lug at the toe; and removable calks at the heel ends of said 25 bar with means for securing the same in place, as and for the purpose specified.

In witness whereof, I, hereunto subscribe my name this 18th day of June, A. D., 1912.

WILLIAM S. McCACKEN.
